UNITED STATES PATENT OFFICE.

GEORGE A. MISUN, OF MILWAUKIE, OREGON.

SHADOWLESS LANTERN.

1,262,968.

Specification of Letters Patent. Patented Apr. 16, 1918.

Application filed August 13, 1917. Serial No. 185,992.

To all whom it may concern:

Be it known that I, GEORGE A. MISUN, a subject of the Emperor of Austria, residing at Milwaukie, in the county of Clackamas and State of Oregon, have invented certain new and useful Improvements in Shadowless Lanterns; and I do declare the following to be a full, clear, and exact description of the invention, such as will enable others skilled in the art to which it appertains to make and use the same.

This invention relates generally to illuminating devices, and more particularly to certain new and useful improvements in lamps or lanterns.

Heretofore, most hand lanterns have been constructed with a supporting base consisting of an oil tank, and this tank has been usually large and prevents the rays of light from radiating downwardly. It is to overcome this difficulty that the present invention is devised, and to this end it consists of a supporting base which is made of comparatively thin and light material which does not obstruct the rays of light any appreciable amount. The fuel tank is located above the burner proper instead of below it.

Another object of the invention is to provide an improved form of mixing chamber for a burner of this general character.

A further object of the invention is to generally improve upon devices of this class by the provision of a comparatively simple, strong, durable, and inexpensive construction, one which will be efficient and reliable in operation, and well adapted to the purpose for which it is designed.

With these and numerous other objects in view, the invention consists of certain novel features of construction, and the combination and arrangement of parts as will be hereinafter fully described and claimed.

In the accompanying drawings in which similar reference characters are used to designate like parts throughout the several views:

Figure 1 is a central vertical sectional view through a lantern constructed in accordance with this invention;

Fig. 2 is a horizontal sectional view taken on the plane indicated by the line 2—2 of Fig. 1;

Fig. 3 is a vertical sectional view of a portion of a lantern illustrating the manner in which the globe is fixed to the same and illustrating it in its two positions;

Fig. 4 is a vertical sectional view of a portion of the lantern taken on the plane indicated by the line 4—4 of Fig. 1; and,

Fig. 5 is a detail sectional view taken on the plane indicated by the line 5—5 of Fig. 1.

Referring more particularly to the drawings, the numeral 1 designates a fuel tank, which is of cylindrical construction, having a convexo-concave top 2 secured thereon in any suitable manner and provided with a filling opening 3 having a cap 4 fitted therein. The cap 4 is provided with an inwardly opening spring pressed valve 5 in order that air may be pumped into the tank should it be found that the force of gravity is not sufficient to cause the fuel to run to the burner. The bottom of the tank 1 is provided with a downwardly projecting eccentrically arranged nipple 6, the purpose of which will be hereinafter described.

The nipple 6 extends through suitable openings arranged in an asbestos plate 7 and a metallic crown plate 8, the latter forming the top of a cylindrical casing 9. As shown, the upper end of the casing 9 is provided with a horizontally disposed outwardly extending annular flange 10, and has its upper side contacting with the lower side of the plate 8 and is secured thereto by means of bolts 11, which have an additional function to be hereinafter described. The walls of the casing 9 are perforated as at 12 to provide proper ventilation in the same, as will be obvious.

Threaded to the nipple 6 is the upper end of a short tube section 13, the lower end of which is likewise secured to a small casing 14 having a needle valve 15 mounted therein. The stem of this valve extends through one of the perforations in the wall of the casing 9 and has a knob 16 arranged on the outer end thereof by which the valve may be operated.

Threaded to the casing 14 and extending horizontally inwardly from the same is a pipe section 17, the inner end of which is bent upwardly and extended through an opening arranged in a cap member 18 which is threaded to the lower open end of a vertically disposed mixing chamber 19. The horizontal pipe section 17 contains a wick 20 of hemp or other suitable material, and threaded in the free end of this pipe section is a nozzle 21.

The mixing chamber 19 constitutes the

vertically disposed portion of a casing having inverted U-shaped portions 22 communicating with said vertically disposed portion by means of a narrow neck 23. This casing 5 is arranged beneath the crown plate 8 centrally of the same, and secured thereto by a bolt 24 which extends through the crown plate and through a lug formed on the top of said casing. Formed at the top of the 10 casing on the interior of the same above the neck 23 and between the inverted U-shaped portions 22, is a rib 25, the purpose of which is to divide the gases as they pass from the mixing chamber 19 through the neck 23 and 15 cause them to flow around the U-shaped portions 22 into tubes 26 which are threaded at their upper ends to said U-shaped portions and which are provided at their lower ends with suitable burners in the form of incan- 20 descent mantles 27. As shown, these mantles 27 are disposed a suitable distance below the plane of the lower end of the casing 9.

The mixing chamber 19 is provided with an internally threaded opening in one side 25 thereof in which is fitted the inner end of an air pipe 28. This air pipe 28 inclines downwardly from its point of connection with the mixing chamber and has its outer end extended through the wall of the casing 9 near 30 the lower end of the same and curved downwardly. By this construction air from the outside atmosphere may be conveyed into the mixing chamber without any danger of rain or dust gaining entrance to the same.

35 The numerals 29 represent inwardly extending stops which are secured to the inner wall of the casing 9 near the lower end of the same. Resting against these stops 29 is the annular flange 30 formed at the upper 40 end of an inverted transparent globe 31, the lower end of which is provided with air inlet openings 32. This flange 30 extends outwardly of the globe and is of a diameter substantially equal to the internal diameter of 45 the casing 9, to cause a rather snug fitting in the lower end of the same.

Secured to one side of the casing 9 is a lug 50 having an eye at its lower end which forms a hinged portion for a U-shaped resilient 55 clamping member 34. This member 34 surrounds the major portion of the globe 31 directly beneath the flange 30 and holds it in hinged relation with respect to the casing 9. Secured to the other side of the casing 9 is a resilient hook 35, the hooked portion of which is adapted to engage the lower side of the flange 30 of the globe 31. This construction provides a means for connecting the globe to the casing 9, and yet permits 60 the former to be swung out of the way when lighting the lantern.

The supporting base for the lantern comprises an annular base member 36 which is arranged horizontally below the lowermost 65 portion of the globe 31. Secured at their

lower ends by rivets or otherwise to this annular base member 36 is a plurality of substantially upright standards 37. These standards 37 consist of flat strips and have their upper ends bent integrally as at 38 over the 70 heretofore mentioned flange 10 and ground plate 8, and are secured to these parts by the bolts 11. The strips are then struck upwardly and have their extreme ends offset outwardly to form ears 39 to which are pivoted the lower ends of a bail-shaped handle 40.

The intermediate portions of the strips or standards 37 are twisted into planes disposed at right-angles to their ends so that 80 they extend edge to edge in radial directions in order not to form an obstruction to the rays of light from the burners.

In using the device, suitable hydrocarbon fuel is placed in the tank 1 and from this it 85 passes through the pipe section 13 into the valve chamber 14. The valve 15 controls the supply of fuel into the pipe section 17. The wick 20 disposed within this pipe section 17 causes a partial vaporization of the fuel before it reaches the nozzle 21, a complete vaporization taking place as it issues from the latter in the form of a spray and mixes with the air conveyed into the mixing chamber through the pipe 28. The mixed gases then 90 pass upwardly through the neck 23 and divide, some of them passing downwardly through one of the tubes 26, while the remainder passes downwardly through the other tube 26. The heat from the burners 95 27 causes a quick vaporization of the fuel. In first lighting the lantern it is necessary to heat the various parts with a match before applying it to the burners. The asbestos plate 7 prevents the fuel tank 1 from 100 becoming heated from the heat from the burners 27, and consequently eliminates the danger of explosion of the fuel.

From the foregoing description, taken in connection with the accompanying drawings, it will be seen that the objects of the invention have been effectively carried out, as the supporting base of the lantern is of such skeleton structure that it will not obstruct an appreciable amount of the rays 115 of light from the burners.

As various changes in form, proportion, and in the minor details of construction may be resorted to without departing from the spirit of this invention, it is to be understood that I do not wish to be limited to the precise construction herein shown and described.

I claim:

1. In a lantern of the class described, the 125 combination with a fuel tank having a burner depending therefrom; of a horizontally arranged annular base member disposed below said tank and said burner, a plurality of substantially upright standards se- 130

cured at their upper ends to said tank and at their lower ends to said base member, said standards being formed of flat strips and having their intermediate portions twisted into planes disposed at right angles to their ends, said intermediate portions of said strips extending edge to edge in radial directions.

2. In a lantern of the class described, the combination of a cylindrical fuel tank, a cylindrical casing disposed below said tank and having an open lower end, said casing being substantially equal in diameter with said tank and having an annular outwardly extending horizontally disposed flange at its upper end, a burner depending from said tank and disposed below the plane of the lower end of said casing, a horizontally arranged annular base member disposed in a plane below said burner, a plurality of substantially upright standards composed of flat strips and having their lower ends secured to said base member, the upper ends of said strips being bent inwardly over the upper side of said annular flange and bolted thereto, then struck upwardly and offset

outwardly to form ears, and a bail-shaped handle pivotally connected at its ends to said ears.

3. In a device of the class described, the combination of a cylindrical casing open at its lower end, a mixing chamber disposed within said casing, a burner depending from said mixing chamber, stops projecting inwardly from the inner wall of said casing and spaced from the lower edge of the same, an inverted globe having an annular flange extending outwardly from the upper edge thereof and resting against said stops, a U-shaped resilient member hinged at its central portion to one side of said casing and partially encircling the wall of said globe beneath said flange, and a resilient hook secured to the opposite side of said casing and engaging the lower side of said flange. 40 45

In testimony whereof I have hereunto set my hand in the presence of two subscribing witnesses.
